SOLDERLESS ELECTRICAL CONNECTOR

Edward E. Leach, White Bear Lake, Minn., assignor to
Minnesota Mining and Manufacturing Company, St.
Paul, Minn., a corporation of Delaware

Filed Feb. 21, 1961, Ser. No. 64,012

Term of patent 14 years

(Cl. D26—1)

FIG. 1

FIG. 2

FIG. 3

FIG. 4

FIG. 5

FIG. 6

FIGURE 1 is a side elevational view of a solderless electrical connector showing my new design;
FIGURE 2 is a top plan view;
FIGURE 3 is an end elevation from the open end, and
FIGURE 4 is an end elevation from the closed opposite end;

FIGURE 5 is a bottom plan view; and
FIGURE 6 is a view in perspective of the connector.
I claim:
The ornamental design for a solderless electrical connector, as shown.
